(57) CLAIM

The ornamental design for a backpack pocket, as shown and described.

DESCRIPTION

FIG. 1 is a perspective view of a backpack pocket; FIG. 2 is a front elevation view thereof; FIG. 3 is a rear elevation view thereof; FIG. 4 is a left elevation view thereof; FIG. 5 is a right elevation view thereof; FIG. 6 is a top planar view thereof; and, FIG. 7 is a bottom planar view thereof. The broken lines shown in the drawings depict portions of a backpack that form no part of the claimed invention.
